Wildt and Company Limited, Leicester, Eng-
land, a British company

Application September 2, 1948, Serial No. 47,494
In Great Britain September 22, 1947

20 Claims. (Cl. 66—79)

1

This invention relates to knitting machines, and has for its primary object to provide an improved and particularly compact wholly automatic full fashioned hosiery machine of fine gauge and comprising a single head adapted to produce fully fashioned stocking blanks having continuously knitted leg and complete heel and foot portions.

According to this invention there is provided a full fashioned knitting machine with a single head characterised by the inclusion of a vertically movable curved needle bed, furnished with an arcuate series of fixed spring bearded needles.

Advantageously the vertically movable needle bed is in the form of a circle an arc of which is occupied by the series of fixed bearded needles.

For co-operation with the said needles for loop forming purposes the machine is essentially provided with an arcuate series of individually movable instruments, combined with means for actuating some, e. g. alternate ones, of the instruments seriatim to position (sink) yarn between spaced needles, and means for effecting simultaneous actuation of all of the said instruments for ensuring that the yarn is drawn around all of the needles knitting at any one time, an operation commonly known as "dividing." For the sake of convenience in the following further description, such instruments will be referred to as "sinkers."

The loops must, of course, be uniformly drawn around the needles when dividing. Consequently, when effecting simultaneous actuation of the sinkers for dividing, this actuation must be uniform, that is to say, the extents of the radial inward and outward movements of the respective sinkers must, so far as is practicable, be the same. To achieve this result it is advantageous to employ individually movable actuating members, adapted to receive operative movements from vertically operable actuating means and to transmit such movements horizontally to the sinkers. The said members may conveniently consist of suitably fulcrumed bell crank levers.

The improved machine also essentially includes a series of independent beard pressers, one to each needle, arranged in an arcuate series of groups, one of the pressers of each such group being formed for operation by suitable cam means and adapted to transmit its movements to the companion pressers of the group. In this way simultaneous operation of all of the pressers is satisfactorily obtainable from

2

an oscillatory cam unit also arranged concentrically with respect to the axis of the machine.

The needle bed with its arcuate series of fixed needles is stationary so far as angular movement is concerned, and there are provided individually operable yarn carriers which are movable angularly to variable extents, as determined by suitably controlled angularly movable stops, about the axis of the machine. This construction is not only such as to obviate the necessity for yarn carrier bars which project beyond the ends of the needle bar (as in a straight-bar machine) but also enables the control mechanism for the yarn carrier stops to be compactly located at the back of the machine.

For narrowing and widening a fully fashioned hose blank there is provided, for operation in conjunction with the appropriate yarn carrier stops, mechanism comprising groups of transfer points, arranged at respectively opposite ends of the arcuate series of needles, and adapted to receive knitted loops from appropriate needles and, after lateral displacement thereof conjointly with vertical movement of the needle bar, to shed such loops for reception by receiving needles. The said transfer points are made flexible to enable them to be deflected over the needle beards during transfer operations.

The machine head also includes automatically operable mechanism for producing a welt. Preferably this mechanism is combined with ancillary mechanism for producing picot courses.

Now stocking blanks of the kind concerned have heretofore often been produced on full fashioned multiple-head machines capable of producing as many as, say, twenty-four blanks at a time. In such a multiple-head machine the knitting operations at the respective heads are carried on simultaneously, and certain instrumentalities are common at all the heads and are controlled by mechanism at the extreme ends of the machine. The long carrier bars for the various components in a multiple-head machine tend temporarily to vary somewhat in length, owing to temperature changes, this resulting at times in inaccurate registration of the co-operating instrumentalities.

Moreover, on a multiple-head machine when one head requires attention the remaining heads must necessarily be idle pending required adjustments. To obviate these, amongst other, disadvantages, single head machines are a desideratum. But, heretofore, single head machines have been designed on the "straight-bar" principle, and as a consequence have occupied consider-

able space. Accordingly, an important advantage arising from the employment of numbers of single head machines constructed with arcuate needle beds in accordance with the present invention, is that economy of space is effected. This is possible because the improved machine is built about a central axis.

In order that the invention may be more clearly understood and readily carried into practical effect, a specific example of the improved single head full fashioned hosiery knitting machine embodying the foregoing and other features of the invention will now be described with reference to the accompanying drawings, wherein,

Figures 1 and 1A together constitute a vertical sectional view through the head of the said machine,

Figure 2 is a plan view of so much of the machine as is necessary to illustrate the curved needle bed, this view being partly in section and taken on the line 11—11 of Figure 1, that is to say with the upper portion of the head of the machine removed for clarity.

Figure 3 is a perspective view of the transfer head for narrowing and widening,

Figure 4 is a perspective view of one of the oscillatory yarn carriers of the machine showing in addition mechanism whereby it is operated,

Figure 5 is a plan view of the upper part of the machine, showing the arrangement of the inside and the outside yarn carrier stops,

Figure 5A is a side elevational view, partly in section, corresponding to Figure 5,

Figure 6 is a detail perspective view of a group of the sinkers and associated needle beard pressers and sinker-operating instruments,

Figures 7, 8 and 9 are side elevational views, partly in section, showing successive stages in the cycle of conjoint movements of the sinkers and their operating instrumentalities,

Figure 10 is a fragmentary plan view of cam means whereby the pressers are operated in groups, as will be hereinafter described,

Figure 11 is a detail end view of the sinkers and pressers, as seen in the direction of the arrow B in Figure 6, showing interengagement of the said pressers for operation in a group,

Figure 12 is a fragmentary view of the sinker-presser bed,

Figures 13-24 are diagrammatic views illustrating successive stages in the conjoint operation of needles and associated instrumentalities in forming a welt,

Figure 25 illustrates diagrammatically the relationship of welt instruments to the needles and sinkers when commencing a welt, and shows the picot instruments inoperative,

Figures 26-28 are further somewhat similar views showing the manner in which a picot course is knitted.

Figure 29 is a detail part sectional view illustrating the mechanism by which the welt and picot instruments are operated,

Figure 30 shows a complete fully fashioned hose blank having a picot edge produced in accordance with this invention,

Figure 31 is a part-sectional view showing a portion of the lower part of the machine head and the controlling mechanism for the needle bed and the sinker operating means,

Figure 32 is a part-sectional side view of the means provided for controlling the transfer head and some of the instruments of the machine,

Figure 33 is a side view of the means employed

for operating the swing lever cam ring hereinafter to be described, and

Figure 34 is a part-sectional side view illustrating the control means for the pressers and the yarn carriers.

Like parts are designated by similar reference characters throughout the drawings.

The needle bed

The needle bed 1 is in the form of a ring (see Figure 2) which, as shown in Figure 1, has an upwardly extending tricked and drilled segmental portion 2 for reception of a series of fixed bearded needles 3. The bed is tricked at 4 and drilled at 5 and the needles are housed in the manner conventionally adopted in straight bar fully fashioned hose knitting machines. For securing the needles in position within the bed there is provided, again as shown in Figure 1, a steel strap 6 located between axially spaced protuberant portions formed on the segmentally shaped tricked and drilled portion 2, this strap extending over the fronts of the shanks of the needles 3 and being secured at its opposite ends to the bed by a straining and locking device (not shown).

The needle bed is concentric with respect to the vertical axis of the machine and is movable up and down to impart the required knitting movement to the bearded needles 3. The lower portion of the ring constituting the needle bed 1 is supported, located and secured upon a carrier ring 7. The carrier ring is peripherally recessed at 8 (Figure 1) suchwise as to provide an annular shoulder 9 adapted to locate the needle bed concentrically therewith and to provide a supporting ledge for the bed. The ring 7, moreover, is formed at a location near to the front of the machine with a downwardly extending boss 10 in which is secured the upper end of a vertical shaft 11 serving both to locate and to operate the needle bed 1. Mechanism presently to be described is provided for action upon this shaft for the purpose of effecting desired vertical movements of the needle bed. In conjunction with this shaft and at a location diametrically opposite thereto, there is provided a fixed vertical guide 12 (Figure 1A) with the sides of which make contact a pair of rollers 13 and 14 carried by an adjustable block 15 mounted on the carrier ring 7. For effecting adjustment of the block 15 there are provided two screws 16 which, as shown more clearly in Figure 1A, are arranged in downwardly directed lugs 17 integral with the carrier ring with their leading ends in contact with the block. The purpose of this adjustment is to maintain concentricity of the needle bed with respect to the axis of the machine. The locating and operating shaft 11 extends through axially spaced bushes 18 integral with a bearing bracket 19 having bearing flanges 20 the upper one of which is adapted to function as a stop for a purpose hereinafter to be described.

Dividing and loop forming

For operating conjointly with the bearded needles 3 there is provided an arcuate series of sinkers 21, one to each needle and alternate ones 21d of which function as dividers, these sinkers 21 being mounted in two radially grooved beds 22 and 23 arranged one above the other and disposed at right angles to the axis of the machine. Each of the sinkers 21 and 21d may be either of the known type having a single loop-forming throat or, as shown, a divided sinker having two throats.

To the opposite sides of each sinker are attached stiffening pieces 24 (Figure 1). Each sinker, moreover, has two downwardly projecting and spaced lugs 25 provided for engagement with a sinker-operating instrument 26 adapted for actuation suchwise as to impart to the sinker its required radial movements. As depicted in Figures 1, 6, 7, 8, and 9, each sinker-operating instrument 26 is in the form of a bellcrank lever formed with a semi-circular open-ended slot 27 constituting its fulcrum point. At its opposite ends each of the said instruments has substantially ball-shaped formations 28 and 29 designed to operate between parallel engaging faces. Thus, the ball-shaped formation 29 at the end of the vertically disposed arm of the instrument 26 operates in the recess formed by the spaced lugs 25 depending from the corresponding sinker, whilst the formation 28 at the inner end of the horizontally disposed arm of the said instrument operates between cam faces to be referred to later. To the respectively opposite sides of the vertical sinker-engaging arm of each sinker-operating instrument 26 there are attached two thin plates 30 of a width greater than the length of the aforesaid recess so that they embrace the opposite sides of the lugs 25 and thereby maintain engagement of the instrument with the sinker, laterally. The semi-circular portions of the open-ended slots 27 constituting the fulcrum points of the sinker-operating instruments 26 are seated upon a complementarily shaped protuberant portion 31 of a ring 32 (Figure 1) whereby the instruments are permitted rocking movement. To maintain engagement of the instruments 26 with the protuberant fulcrum 31 there is a ring 33 which is formed with grooves 33a, one to each instrument 26, to receive curved portions of the said instruments, the grooves extending tangentially with respect to the curved portions. The un-cut ring 32 formed with the protuberant fulcrum 31, and the grooved ring 33 are both attached to the machine bed 34. All of the sinker-operating instruments 26 are rocked together to effect simultaneous radial sliding movements of the sinkers 21 and 21d.

For the purpose of sinking the loop, i. e. initially laying yarn between alternate ones of the needles 3, alternate sinkers 21 are acted upon by swing levers 35 which are fulcrumed upon a circular-sectioned arcuate rib 36 (Figure 1) formed on a swing lever carrier ring 37 having tricks 38 cut to accommodate the levers and disposed above the sinkers. Each swing lever 35 is formed at its upper end with a hook-shaped fulcrum portion 39 mounted to swing on the arcuate rib 36. The operative ends 40 of the swing levers 35 are inwardly directed and arranged for contact with the tail ends 41 of the alternate sinkers 21. For actuating the swing levers 35 there is provided a cam 42 mounted, as illustrated in Figure 1, on an oscillatory swing lever cam ring 43 and adapted for action upon the said levers seriatim. This cam 42 acts upon each swing lever 35 at a location adjacent to the cut portion or trick 38 of the swing lever carrier ring 37. To maintain the hook-shaped fulcrum portions 39 of the swing levers 35 in engagement with the circular-sectioned arcuate rib 36 there is provided a sectional ring 44 having on its underside a flat face 45 which contacts and is tangential with respect to the outer curved edges 46 of the hook-shaped fulcrum portions 39.

Independent pressers

The machine includes a series of independent

beard pressers 47, one to each needle, mounted in the upper sinker bed 23. In this connection each of the pressers 47 has a stepped formation 48 at one side which, and as depicted in Figure 12, provides a slot 49 of a width narrower than that of a presser trick 50 for accommodation of the upper edge of the companion sinker 21 or 21d as the case may be. This construction enables the sinkers and the pressers 47 to be actuated independently of each other. Each of the pressers 47 is formed at its operative end with an appropriately shaped portion 51 for contact with the needle beards at required times. Apart from this, the pressers are of two types, viz: one with an upstanding butt 52 on the upper edge of its stem and the other with a plain non-butted stem 53. At its outer end each of the butted pressers is formed with an initially rearwardly directed lug 54 which is split longitudinally, the split portions being bent in such a way as to provide tail formations 55 and 56 extending laterally from opposite sides of the presser—at right angles thereto. Each of the non-butted pressers has formed therein adjacent to its outer extremity an open-ended vertical slot 57 (Figure 6). The pressers are preferably, and as shown in Figures 6, 10 and 11, arranged in groups of three throughout the series, each group comprising one of the butted pressers and two non-butted pressers, with the non-butted pressers disposed one at each side of the said butted presser and with the lateral tail formations 55 and 56 of the latter engaged in the vertical slots 57 of the non-butted pressers. By reason of this arrangement all three pressers of a group are moved together when the upstanding butt 52 of the central presser is acted upon.

Housing sinkers and pressers

The lower sinker bed 22, which is in the form of a ring, is formed with a concentric downwardly extending annular portion 58 (Figure 1) which is fitted into an annularly recessed upstanding part 59 of the machine bed 34, these two parts being bolted together by means of bolts 60. A segmental portion 61 of the upper horizontal face of the lower sinker bed 22 is cut, as shown in Figure 2, to provide therein radial grooves 62 in which the lower edges of the arcuate series of sinkers 21 and 21d are located. The upper sinker bed 23 which also accommodates the pressers 47, and will accordingly for the sake of convenience be referred to as the "sinker-presser" bed, is likewise in the form of a ring, a segmental portion of the lower horizontal face of which is cut with radial grooves constituting the presser tricks 50 (Figure 12). These grooves are cut to the width of the pressers 47. The stepped portion 48 of each of the pressers 47 therefore in effect forms one wall of a trick of narrower width to accommodate the upper edge of the companion sinker, as hereinbefore described, the opposite wall of such trick being constituted by the appropriate side of the radial groove 50 in which the presser is located. The upper face of the sinker-presser bed 23 is annularly recessed as indicated at 63 in Figure 12, the central portion of the bottom of this recess being again similarly recessed at 64 to a greater depth to expose the radial grooves 50. Fitted within the recessed face of the sinker-presser bed 23 is a presser operating cam unit comprising concentrically disposed inner and outer radially spaced cam rings 65 and 66 adapted to provide between them, as illustrated in Figure 10, a cam track 67. These cam rings are attached to the underside of and thereby connected

by a carrier ring 68 (Figure 1) also accommodated in the recessed face. The presser operating cam unit is arranged for limited oscillatory movement relatively to the sinker-presser bed 23. The opposed edges of the cam rings 65 and 66 are formed with arcuate series of oppositely cut saw teeth 65a and 66a constituting cam formations adapted as and when the presser operating cam unit is oscillated, to act upon the ends of the presser butts 52 projecting upwards through the exposed radial grooves 50 for the purpose of imparting to the pressers 47 their required endwise movements. Each pair of opposed saw teeth 65a, 66a is for action upon one presser butt 52 and therefore actuates three pressers 47 in all as shown in Figure 6. As three pressers are actuated by one butt only, the pitch of the saw teeth can equal one group of pressers, this allowing a sufficient length of cam surface for adequate endwise movement of the pressers when the oscillatory presser operating cam unit is operated. To retain the presser-operating cam unit within the sinker-presser bed 23 the recessed face 63 of the latter has attached thereto an annular cover plate 69. The lower sinker bed 22 and the sinker-presser bed 23 are spaced apart axially and accurately located concentrically by means of a segmentally shaped spacing and locating piece 70 secured between the uncut portions of these beds at the rear of the machine as illustrated in Figure 1A. The annular cover plate 69 is peripherally recessed to receive the swinging lever carrier ring 37. The swing lever retaining ring 44 is mounted on a peripherally recessed upper portion of the swing lever carrier ring 37, these parts being secured together and to the annular cover plate 69 by means of bolts 71 and the cover plate being, in turn, bolted to the sinker-presser bed 23 by means of further bolts 72.

Supported from the machine bed 34 by means of supporting posts such as that indicated at 73 in Figure 1 is a circular housing 74 for the swing lever cam ring 43. Located in the top of the housing 74 is a circular casting 75 which serves to support mechanism carrying stops for the yarn feeders to be hereinafter described. In addition, the casting 75 is made with a stepped formation providing an annular ledge 76 adapted to carry segmental plates 77 used for the purpose of supporting the superimposed series of rings 69, 37 and 44 fixed upon the sinker-presser bed 23. Each of the segmental supporting plates 77 is tenoned at 78 on its underside to locate it between the casting 75 and the swing lever retaining ring 44, the plate being bolted by means of bolts 79 to these parts to ensure rigidity of the sinker-presser bed 23 and its associated parts.

Operation of the swing lever cam ring

The oscillatory swing lever cam ring 43 is operable by suitable gearing, including gear teeth on ring 43, pinion 80, vertical shaft 81 and bevel pinion 82 (Figure 1A) from a continuously rotatable cam shaft 290. To this shaft is secured a gear 291 arranged in mesh with a gear 292 on the main cam shaft 218, the arrangement being such as to obtain a speed of the shaft 290 half that of the shaft 218. Secured to the shaft 290 is a track cam 293 in which is formed a cam groove 294. Engaging in the groove 294 is a roller 295 which is carried by an arm 296 fixed to a rack slide 297 suitably mounted in the machine framing. To effect the necessary reciprocatory movement, a pinion 298, arranged in mesh with the rack slide 297, is rigidly secured upon a shaft

10

299 to which is also secured a bevel gear 300. The gear 300 engages the bevel pinion 82 secured upon the lower end of the vertical shaft 81. By these means oscillatory movement is imparted to the swing lever cam ring 43. As is common in full-fashioned knitting machines, a clutch operable to stop the reciprocatory movement during narrowing and widening movements, is provided but is not shown.

Yarn feeding means

The machine is equipped with a plurality of independently operable yarn carriers, such as 83 (Figures 1 and 4) say eight—five of which may be used for supplying ground yarns for conventional knitting operations whilst the remaining three are splicing yarn carriers. These carriers 83 are arranged for oscillatory movement about the axis *a* of the machine. The upper ends 84 of the carriers 83 are disposed one above another, and are so formed that they extend first outwardly from these ends and thence downwards. To the lower end 85 of each yarn carrier is adjustably attached an inwardly inclined feeding element 86 for laying the yarn in the sinker throats. The downwardly extending portions of the yarn carriers 83 are disposed at progressively greater distances radially from the axis *a* of the machine, the carrier nearest to this axis having its upper end lowermost and the upper ends of the remaining carriers, in order, being at progressively higher elevations. As a consequence of this arrangement the yarn carriers can, of course, be oscillated independently without the yarn feeding elements 86 of the yarns supplied thereby fouling one another. The upper end 84 of each yarn carrier 83 has attached to its underside a pinion 87 from which depends a tubular shaft 88. These shafts are of respectively different diameters and arranged to fit or nest compactly one within another. To enable the diameters of the tubular shafts 88 to be restricted the said shafts are arranged in two groups, one of which is fitted into the upper end of a central vertical fixed shaft 89, whilst the other is similarly fitted into a bossed bracket 90 (Figure 1A) disposed above the fixed shaft. The pinions 87 with the attached ends 84 of the yarn carriers 83 are therefore disposed one above another in a bank between the fixed shaft 89 and the bossed bracket 90. Arranged in mesh with each pinion 87 is a sector gear 91 which, when oscillated, imparts corresponding oscillatory movement to the pinion. The sector gears 91 are disposed one above another in the respectively different horizontal planes occupied by the corresponding pinions 87 and are suitably spaced apart by means of spacing pieces 92. These pieces 92 are formed, as also are the upper end portions 84 of the yarn carriers attached to the pinions, with yarn-guiding slots 93. Hardened pegs 94 extending transversely across the slots 93 are provided for guiding the yarns and also maintaining the latter within the slots during oscillatory movements of the yarn carriers. For laying desired yarns the yarn carriers 83 are operated selectively by selective actuation of the sector gears 91. For this purpose there is provided in conjunction with the said gears a V-shaped selecting lever 95 which, as shown in Figure 4, is formed with inwardly curved operative ends 96 and is selectively movable heightwise into one of the horizontal planes occupied by the sector gears 91. The said inwardly curved operative ends 96 are disposed for action respectively upon

opposite sides of pivoted arms 97 upon which the sector gears 91 are formed. Thus, by moving the selecting lever 95 to the required plane by means later to be described and then imparting thereto oscillatory movement it is caused to act first on one side and then the other of the appropriate sector gear 91, thereby imparting movement to the sector gear and hence also to the corresponding yarn carrier 83 first in one direction and then in the opposite direction. 10 The space between the inwardly curved operative ends 96 of the V-shaped selecting lever 95 is sufficient to allow the latter, whenever returned to a central neutral position preparatory to movement heightwise into another plane, to avoid contact with sector gear arms 97 disposed at the extremities—both right hand and left hand—of their movements. The selecting lever 95 is provided with an elongated vertical boss 98 which is bushed at opposite ends and mounted slidably upon a fixed vertical shaft 99 constituting the pivot of the said lever. The shaft 99 is fixed at its lower end into an upper machine casting 100 and in the bracket 90 at its upper end. In the tail end of the V-shaped selecting lever 95 is formed a hole in which is secured a vertical operating rod 101 the upper end of which is connected to the elongated vertical boss 98 by means of a connecting plate 102 (Figure 1A). The operating rod 101 is permanently engaged between inwardly directed ends of a forked lever 103 (Figure 4) adapted to be oscillated from a control lever 301 (see Figure 34) through the medium of a shaft 104 having resilient action in both directions by reason of the provision of springs 105 and collars 106 so that although the shaft 104 has a movement of a constant distance in either direction, the yarn carrier 83 may have varied angular travel, according to the different positions of the yarn carriers stops.

For operating the shaft 104, there is provided a stud 302 (Figure 34) which is fixed at its upper end to the said shaft and at its lower end to a control lever 301. The last mentioned lever is in turn secured to the upper end of a spindle 303 mounted for turning movement in a bearing in a bracket 304 and also in a bearing 305. To the lower end of the spindle 303 is rigidly secured the fulcrum end of a lever 306 the opposite end of which latter is furnished with a roller 307 adapted to be operated upon by a rotary face cam 308 secured upon the continuously rotatable cam shaft 290.

Welt forming and picot mechanism

This mechanism includes, as shown in Figures 1 and 29, a horizontally disposed annular "welt-picot" bed 107 arranged concentrically within the needle bed 1 and a segmental portion of which is cut to provide therein radial grooves 108 spaced according to the spacing of the needles 3. The welt-picot bed 107 is mounted upon stepped supporting and locating portion of a casting 109 which is in turn secured upon the centre shaft 89 of the machine head. Within alternate radial grooves 108 cut in the welt-picot bed 107 are located two companion instruments 110 adapted for operation conjointly. These pairs of instruments are for forming a welt. Single instruments 111 are located in the intervening grooves 108 for the transfer of sinker loops. The instruments 110 and 111 are formed with upstanding operating butts 112 and 113 respectively. For engagement with the operating butts 112 and 113 there are provided actuating

elements 114 and 115, there being one element 114 for each pair of instruments 110 and one element 115 for each instrument 111. The actuating elements 114 and 115 are fulcrumed at 5 116 between their ends, the lower ends being forked for engagement with the operating butts 112 and 113, whilst the upper ends are appropriately formed for engagement by vertically movable cam means whereby the elements are rocked to impart horizontal movement to the instruments. The actuating elements, moreover, are of two forms having their upper ends in respectively different planes heightwise. The elements 114 with upper ends in the lower plane alternate with elements 115 having their upper ends in the higher plane.

The fulcrum seating 116 engaging the rounded portions 117 of the elements 114 and 115 consists of a circular sectioned rib formed on the casting 109. For holding down the welt-picot instruments 110 and 111 and for maintaining the elements 114 and 115 in their operative positions the said elements are formed with protuberances 118 which are arranged in engagement with a concavity 119 formed concentrically with respect to the rib 116 on the casting 109. Attached to this casting is a partially tricked ring 120 through the tricks in which the elements 114 and 115 extend for engagement at their lower ends with the welt-picot instruments. The lower end of the casting 109 seats in an annular recess formed adjacent to the radially grooved upper face of the welt-picot bed 107.

The aforementioned vertically movable means for rocking the actuating elements consist of two pairs of spaced rings disposed in different planes heightwise. Thus, the ball-shaped ends 121 of the elements 114 are located between rings 122 and 123 attached to a flanged boss 124 by screws 125, the said boss being slotted to accommodate a roller 126 (Figure 1A) arranged in engagement with a slotted portion of a bell crank lever 127. This lever is furnished with a pin 128 located in a vertical slot 129 formed in a slide 130 housed in a radially slotted portion 131 of the welt-picot bed 107 (see Figure 1A). The slide 130 is in turn formed with a vertically slotted part 132 which is engaged with an operating rod 133 adapted to be actuated from the main controlling means of the machine by means of a lever 310 which is fulcrumed at 311 and is jointed at 312 to the operating rod 133 in the manner depicted in Figure 32. A roller 313 carried by the upper end of the lever 310 is arranged to contact a group of cams 225 (Figure 5) which are slidably mounted on the main cam shaft 218. The reference numerals 314, 315 and 316 indicate a nest of concentric shafts to any one of which is secured an arm such as 317 by means of which the group of cams 225 is shiftable axially whenever it is required to impart an appropriate movement to the lever 310 for the purpose of moving the welt-picot unit up or down, through the medium of the operating rod 133, and the bell crank lever 127. By reason of this construction the welt-picot unit can be moved up and down heightwise, according to requirements, whilst maintaining engagement of the rod 133 with the slotted part 132 and without disturbance of the relationship of the lever 127 with the flanged boss 124. The ends 134 of the elements 115 are located between rings 135 and 136 attached to a boss 137 by screws 138, this boss being movable up and down by a lever 318 (Figure 32) which is fulcrumed on shaft 319 and is furnished at its opposite end with a roller

320 arranged in contact with the aforementioned group of cams 225. The boss 137 is for sliding movement on the vertical centre shaft 89—individually of the flanged boss 124 which is similarly slidable upon a sleeve formed integrally with a casting 139 serving to support the welt-picot bed 107.

Narrowing and widening (transfer)

The purpose of the mechanism now to be described is to narrow and widen the stocking blank adjacent to the selvedges for shaping the blank. The mechanism, which may conveniently be called the "transfer head," includes at each end of the arcuate series of co-operating knitting instrumentalities, a group of transfer points. These groups 140 and 141 (Figures 1 and 3) are arranged on an arc to conform with the disposition of the needles 3, the individual transfer points being disposed for action on the beards and the fronts of the needle stems. The transfer points are made flexible, and the two groups of points are movable laterally towards and away from each other in the aforesaid arcuate path. Each of the transfer points is fashioned from a comparatively short length of wire, the operative end of which is formed with a hollowed out inwardly directed pointed formation, adapted to fit over a needle beard. The opposite end of the point is flattened to enable it to be mounted within a groove in a point carrier, and is bent inwardly at right angles at its extremity for engagement within a drilled hole or a slot in the said carrier. Intermediate its ends each point is relieved to enable it to be flexed. The transfer points of each group are mounted vertically within a grooved arcuate carrier 142. To the front of the arcuate carrier 142 is provided a clamp plate 143 which is secured in position by screws 144. Mounted above the arcuate carriers 142 are two superimposed gears 145 and 146, one of the carriers being upwardly flanged at 147 and secured to a depending skirt 148 of the lower gear 145, whilst the other carrier is somewhat similarly flanged and secured to a plain cylindrical portion 149 of the upper gear 146. The flange of the last-mentioned arcuate carrier is formed to avoid the teeth of the lower gear 145. The lower gear is an ordinary spur gear having a single circular series of teeth, whereas the upper gear comprises two spaced circular series of teeth, a lower series of spur teeth and an upper series of worm-engaging teeth 150. The upper and lower gears 145 and 146 are independently mounted for oscillating step-by-step movement upon a cylindrical carrier 151 mounted fixedly upon a flanged boss 152, which is bushed at its opposite ends as indicated at 153 and 154 and mounted for movement vertically upon the centre shaft 89 of the machine head. The said transfer cylindrical carrier 151 is prevented from circumferential movement by means of a vertical bar 155 which engages at its upper end an upper machine casting 100 and at its lower in a bracket 156 (see Figure 1A), which is screwed to the back of the said carrier and has mounted therein a worm 157 arranged in mesh with the worm teeth 150 cut in the upper gear 146. In another bracket 158 secured to the cylindrical carrier 151 at one side of the rear bracket 156, are mounted two pinions 159 and 160, one arranged in mesh with the lower gear and the other in mesh with the spur teeth of the upper gear. The two pinions, although themselves arranged permanently in

mesh, are in partially offset relation axially so that the intermeshing portions thereof are clear of the upper and lower gears 145 and 146. Whenever, therefore, the gear 146 has oscillating step-by-step movement imparted thereto, through the medium of the aforementioned worm gearing 150 and 157, the lower gear 145 is similarly driven but in the reverse manner. For effecting movements of the arcuate transfer point carriers 142 in opposite directions each to the extent of one, two or more needle spaces as may be required, the worm 157 is intermittently rotated in either direction, according to requirements, by gearing controlled by pawl and ratchet mechanism in turn suitably controlled through intermediate means from the main cam shaft of the machine. Thus, for instance, the worm spindle 161 may, as shown in Figure 3, have secured to one end thereof a pinion 162 arranged in mesh with a gear wheel 163 mounted on a shaft 164 with which are integrally formed a pair of reversely cut ratchet wheels 165 and 166, adapted to co-operate with suitably spaced oppositely arranged pawls 167 and 168. Integral with the rack-wheel shaft 164 is a toothed check wheel 169 co-operating with a spring-loaded detent 170. The pawls 167 and 168 are mounted on individually movable slides 171 and 172. Provided on the bracket 156, are two lugs 173 and 174, one arranged in contact with the appropriate face of each pawl, for the purpose of accurately locating the latter upon its operative strokes, and for holding it clear of the teeth of the corresponding ratchet wheel when such wheel is reversely racked. Now as the bearded needles 3 are only capable of movement vertically it is necessary to permit co-operation of the transfer points P with the needles to effect deflection of the said points radially, inwards and outwards relatively to the needles. For this purpose each arcuate transfer point carrier 142 is furnished at its ends with fulcrum pins 175, upon which is mounted a bifurcated part of a rocking lever 176 having a depending arm 177 formed at its lower end with an arcuate cam edge 178 for contact with the flexible portions of the transfer points. The rocking lever 176 is also formed with an inwardly directed arm 179 arranged in contact with the lower edge 180 of an operating ring 181 with which is integrally combined a cylindrical locating portion 182 of a somewhat larger diameter, designed to fit within the cylindrical carrier 151 of the transfer head. The said locating portion is formed with a plurality of obliquely disposed slots 183 in to which extend cam portions 184 formed integrally with an operating ring 185. As a result of this construction, whenever angular movement is imparted to the ring 185, the operating ring 181 is raised and lowered, thereby effecting appropriate actuation of the rocking lever 176 and its cam edge 178, and as a consequence, causing the required deflection of the points. The construction is also such that irrespective of the extent of the lateral movements of the arcuate carriers 142, contact of the operating ring 181 with the upper arm of the rocking levers 176 and hence also operation of the latter will be maintained. The operating ring 181 is fitted with a stud (not shown) which projects upwards through the top of the cylindrical carrier 151, and is connected to suitable control means. The operating ring 181 is held in contact with the operating ring 185 by means of springs 186 anchored to hooks 187 and 188 screwed into the cylindrical carrier 151 and the

ring 181 respectively. Thus, for narrowing and widening purposes, loops on needles adjoining the selvedges are, by conjoint vertical movements of the needle bed and the transfer head, together with relative lateral movements of the arcuate transfer point carriers 142 and deflection of the groups of points, transferred to other needles. Considered specifically, loop transfer is effected as follows:

First, a change is made from the main control to effect cessation of laying of the yarn and knitting, and to initiate transfer of loops. Then the needle bar 1 is moved to position the needles at a height to receive the transfer points P, which latter are moved downwards and simultaneously flexed outwardly, so that they move in a curved path over the needle beards and are located with their tips in the beard grooves. Following this, both the needle bar 1 and the transfer head are moved downwards together, until the knitted loops are safely landed on to the transfer points. At the next stage the transfer points P are again outwardly flexed, the needle bar 1 is moved still further down to withdraw the needles to a low position to permit lateral movement of the groups 140 and 141 of transfer points when clear of the sinkers, and these groups are thereupon moved to bring the points P into alignment with those needles to which the spread loops now on the points are to be transferred. Subsequently, the needle bar 1 is raised to position the needles 3 at the normal clearing height, by which time the appropriate needles have penetrated the spread loops. This upward movement of the needle bed is accompanied by movement upwardly of the transfer head. When, however, the needles 3 reach clearing height, movement of the needle bar 1 is arrested, the continuing upward movement of the transfer head to a position clear of the needle beards, in conjunction with outward deflection of the transfer points P, resulting in disengagement of the said points from the needle beards. Normal knitting is then resumed.

For raising and lowering the transfer head, the central flanged boss 152 (Figures 1 and 1A) is formed with a bifurcated lug 189 to receive a further pivoted link 190 which is, in turn, connected to a rocking lever 191 adapted to be actuated from the main cam shaft 218.

Yarn carrier control stops

As hereinbefore mentioned the yarn carriers 83 are each arranged for oscillatory movement about the axis *a* of the machine. For narrowing and widening purposes it is necessary to vary the angular extents of these movements. There are two groups 192 and 193 of outside yarn carrier stops which are carried by the circular casting 75 and left-hand and right-hand inside splicing yarn carrier stops 194 and 195 respectively, which are located on the underside of the upper machine casting 100. The outside yarn carrier stops 192 and 193 consists of screws fixed into inwardly directed radially disposed bars 196 and 197 fixed in two carriers 198 and 199, mounted for relative sliding movement back and forth angularly on the upper side of the circular casting 75. The carriers 198 and 199 are of a thickness adequate to support the stop bars 196 and 197, whilst portions thereof are reduced in thickness, and arranged in superimposed relation suchwise as to permit collapsibility of the carriers and enable the groups of outside stops 192 and 193 to be simultaneously moved rearwardly towards each other to position the stop bars out of

range of the knitting instrumentalities at such times as the bars are re-set, preparatory to the commencement of a new hose blank. The maximum extent of the forward movement of the carriers 198 and 199 locates the stop bars 196 and 197 in positions conforming to the narrowest section of the knitted blank. As will be understood by moving the stop bars to desired intermediate positions, conjointly with appropriate movements of the transfer points P, shaping of the knitted blank is effected. The two carriers 198 and 199 are held in position by a flanged ring 200 having cut away portions 201 which enable the bar 197 to project inwardly and below the carrier 198, the bar 196 being fixed to the upper face of said last mentioned carrier. A spring 202 located in an annular groove 203 formed in the carrier 199 is anchored at one end to the latter and at its opposite end to the carrier 198. Of the two stop bar carriers that, 198, having the upper reduced portion is formed with an upper series of ratchet teeth 204, extending to an appropriate angular extent. Similarly, the carrier 199 having the lower reduced portion is formed with a lower series of ratchet teeth 205 of a similar extent. The two series of teeth 204 and 205 are cut in respectively opposite directions, the pitch of the teeth corresponding to that of twice the needle pitch. For racking the stop bar carriers 198 and 199 there are provided selectively operable pawls 206 and 207, the operative stroke of each of which can be varied to produce either a rack to the extent of half a ratchet tooth i. e. corresponding to the pitch of the needles, or a rack to the extent of a whole tooth corresponding to twice the needle pitch. In association with the rack pawl 206 there are provided two check pawls 208 and 209, suitably spaced apart so that whilst the tooth engaging end of the one is fully engaged with a tooth 204, the corresponding end of the other is located only half way across a tooth. There also are two check pawls 210 and 211 which are associated with the rack pawl 207 and arranged in a similar way to the pawls 208 and 209, that is to say, whilst the tooth engaging end of one is fully engaged with a tooth 205 the corresponding end of the other is located half way across a tooth. Consequently, whenever either of the rack pawls operates to produce a series of racks each to the extent of half a ratchet tooth, the associated check pawls will register alternately to position the corresponding stop bar carrier. When, on the other hand, a rack pawl operates to produce a series of racks, each to the extent of a whole tooth, one and the same check pawl only registers while the other moves idly over the teeth. The two groups of three pawls are respectively oppositely disposed. Adjacent to the appropriate faces of the rack pawls 206 and 207 are located fixed lugs 212 and 213, adapted whenever the stop bar carriers 198 and 199 are reversely operated, to make contact with these faces and move and hold the pawls clear of the ratchet teeth 204 and 205. The rack pawls of the two groups each of three pawls are pivotally mounted upon fulcrummed levers 214 and 215. For reversely operating the two carriers 198 and 199 there is provided an arcuate slide 216 provided with cam faces 217, 217a and 217b designed for action upon tails on the check pawls of the two groups. All the pawls are spring controlled. The levers 214 and 215 are operated and controlled from the main cam shaft 218 through the medium of cams 219 and 220, levers 221 and 222 and links 223 and 224. The slide 216 is operated from the same

cam shaft 218 by way of the group of cams 225, a lever 226, a link 227 and a lever 228 fulcrumed at 229. The operative end 230 of the lever 228 is formed for engagement within a recess 231 in the slide 216 so that the latter is moved endwise to different extents depending on which of the cams 225 is in engagement with the lever 226. Whenever racking of the pawls 206 and 207 takes place, narrowing is effected, but when widening of the groups of stops 192 and 193 is required, the rack pawls 206 and 207 are withdrawn from action into positions in which they rest against the lugs 212 and 213. Such withdrawal is effected by moving the cams 219 and 220 into their inoperative positions by the control means of the machine. This enables the check pawls 208, 209, 210 and 211 to engage the teeth 204 and 205 against the action of the spring 202. Thus, by now moving the slide 216 endwise in stages, the tail ends of the check pawls 208 and 211 are first acted upon by high portions of the cam faces 217a and 217b to withdraw these pawls from the teeth 204 and 205, thereby enabling the remaining two check pawls 209 and 210, which at this stage are not acted upon by the cam face 217, to engage the said teeth which are now displaced to the extent of half a tooth. At the next stage of movement in the same direction of the slide 216, the tail ends of the check pawls 208 and 211 are allowed to fall back to similar levels of the cam faces 217a and 217b, thus positioning the pawls 208 and 211 for re-engagement with the teeth 204 and 205. The tails of the pawls 209 and 210 are simultaneously moved forward at 217c onto high portions of the slide 216, thereby effecting withdrawal of these two pawls from the teeth 204 and 205. Continued two-stage endwise movements of the slide 216 will result in widening to any required extent, according to the layout of the control means of the machine. It will therefore be appreciated that if the forward check pawl of either group is lifted in this way, the rear check pawl will be permitted to fully engage the appropriate tooth, and conversely, if the rear check pawl is lifted clear of the ratchet teeth the forward check pawl will be permitted similar full engagement with a tooth, to determine the extent of the reverse rack. At the full extent of the endwise movements of the slide 216 both the rack and the check pawls are all disengaged from the ratchet teeth, thereby permitting resetting of the stop bar carriers. As an alternative, the rack pawls may be operated and controlled independently of the check pawls. In any event the contact faces or edges of the two stop bars for action on the outside yarn carriers, may be stepped to vary the relative positions of the said carriers.

The left-hand and right-hand inside splicing stops 194 and 195 are secured respectively to the upper and lower faces of two superimposed ratchet wheels 232 and 233 from the peripheries of which the splicing stops extend radially outwards.

The ratchet wheels 232 and 233 are cut with oppositely directed teeth and located for forward and reverse racking movements upon the outside of a boss 234, which depends from the upper machine casting 100 and is concentric with respect to the machine axis *a*. Beneath the ratchet wheels 232 and 233 and located within the depending boss 234 is a flanged cover-plate, 235 between the outwardly directed flange 236 of which and the underside of the bottom ratchet wheel 233 is accommodated a helical coil spring 237. This spring is anchored at one end to the

cover plate 235 and after extending a suitable distance around the latter is attached at its opposite end to the bottom ratchet wheel 233. In a somewhat similar way the upper machine casting 100 is circumferentially stepped to provide space for reception of another helical coil spring 238, one end of which is anchored to the said casting whilst the other end is attached to the upper ratchet wheel 232. The two springs 237 and 238 urge the respective ratchet wheels 232 and 233 in opposite directions. In association with the said ratchet wheels there are groups of pawls, viz: rack pawls 239 and 240 and check pawls 241 and 242 and 243 and 244 which are similarly arranged, and operable on a similar principle to, the hereinbefore described pawls employed for racking and locating or indexing the outside stop bar carriers 198 and 199. In this case, however, the two oppositely disposed rack pawls 239 and 240 are operated in tandem and independently of the associated check pawls. For this purpose the rack pawl levers 245 and 246 are connected by links 247 and 248 to downwardly extending arms 249 and 250 fast on a common shaft 251 controlled in a manner hereinafter to be described. As regards the two pairs of oppositely functioning check pawls, 241 and 242 and 243 and 244, these are operated and controlled by an arcuate slide 252 common to them all, the inner edge of this slide being appropriately profiled in the same way as the slide 216 to provide cam formations for action on tails on the check pawls in the manner required.

Now, whenever the splicing stops 194 and 195 are re-set by simultaneous rearward movement in opposite directions following disengagement of all the relevant pawls from the ratchet wheels 232 and 233, the splicing yarn carriers will be automatically swept aside by the stop and restored to their inoperative positions. As, however, this is not so with the various carriers controlled by the outside stops, it is necessary to provide means of any appropriate character for restoring such carriers to their starting positions, preparatory to the commencement of knitting each blank.

Mounting of the needle bed

The needle bed 1 and its carrier ring 10 are mounted in such a manner as to enable them to be swung clear of the machine head, in the manner depicted in dot-and-dash lines in Figure 2, at such times as the needle bed requires attention. For this purpose the bracket 19 is fulcrumed upon a shaft 253. When the needle bed 1 is in its normal operative position it is located by reason of engagement of the rollers 13 and 14 with the fixed vertical guide 12, and strict concentricity of the bed with respect to the machine axis *a* can be obtained and maintained by a bracket 254 which is adjustably fixed to a bracket 255 integral with the machine framing and connected by means of a link 256 with a lug 257 on the bracket 19. Preparatory to swinging the needle bed clear of the machine as hereinbefore described, the link 256 is first disengaged from the bracket 254, and then the said bed is lowered until the rollers 13 and 14 are clear of the vertical guide 12.

Control of needle bed

The vertical locating and operating shaft 11 which depends from the needle bed carrier ring 10 and extends through the bracket 19 is connected at its lower end with one arm of a

bell crank lever 321 (see Figure 31) through the medium of a connecting element 322. The element 322 is provided with a lug which is slotted at 323 to receive a pin 324 fixed in the said arm of the bell crank lever 321. This lever is fulcrumed at 325 and is furnished at its end remote from the operating shaft 11 with a roller 326 adapted to be acted upon by the cams 225 on the continuously rotating cam shaft 218 for the purpose of imparting the required vertical movements to the needle bed for knitting, and transferring during narrowing and widening, respectively.

Control of sinkers

The ball-shaped inner ends 28 of the horizontally disposed arms of the sinker-operating instruments 26 are engaged between parallel horizontal faces 258 and 259 respectively on inner and outer arcuate bars 260 and 261, suitably mounted for movement vertically either conjointly, or independently, according to circumstances. The inner arcuate bar 260 is formed at its upper edge with an outwardly directed flange 262, the underside of which constitutes the face 258 and is adapted for engagement with the tops of the ball-shaped inner ends 28 of the sinker-operating instruments 26, whilst the lower edges of the said ends are engageable by the upper edge of the outer arcuate bar 261 constituting the face 259. The said inner and outer arcuate bars 260 and 261 are respectively attached to lower and upper arcuate carriers 263 and 264. The upper arcuate carrier 264 is secured to the upper end of a depending vertical shaft 265 accommodated within a tubular shaft 266 (shown in Figures 2 and 31), upon the upper end of which is attached the lower arcuate carrier 263. The inner and outer shafts 265 and 266 are mounted within the bracket 255 which is bushed at its upper and lower ends.

To the lower ends of the inner and outer shafts 265 and 266 are rigidly secured connecting elements 327 and 328 having pin and slot connections with a pair of two-armed levers 329 and 330, respectively. These two levers are fulcrumed at 331 and connected to the lower ends of vertically disposed links one of which is indicated at 332. At their upper ends the said links 332 are furnished with rollers such as 333 arranged in contact with a group of suitable cams, such as 225, mounted on the cam shaft 218 and adapted to be controlled by a shifting lever 334 secured to any appropriate one of a nest of concentrically arranged shafts 335, 336 and 337.

To enable the sinker-operating instruments 26 to be removed the inner arcuate carrier 260 is adapted to be raised manually to remove its outwardly directed flange 262 out of the range of the ball-shaped inner ends 28 of the instruments as and when these are turned rearwardly on their fulcrums.

When both sinking and dividing takes place the outer arcuate bar 261 is automatically positioned to function as a verge or falling bar.

Control of pressers

The carrier ring 68 of the presser operating cam unit is provided with an upstanding lug 338 (Figure 34) protruding through a slot 339 formed in the associated annular cover plate 69. This lug is engaged by the end 340 of a link 341. The opposite end 342 of the link 341 is connected to a rocking lever 343 which is furnished with a roller 344 arranged for contact with a suitable cam such as 225 on the continuously rotatable

cam shaft 218, all as shown in Figure 34. During narrowing and widening transfer operations the presser operating cam unit is rendered inoperative, for which purpose the said cam is associated with a dwell portion.

Control of yarn feeding means

The V-shaped selecting lever 95 for selectively actuating the pinions 87 provided on the yarn carriers 83, is movable into the hereinbefore mentioned horizontal planes through the medium of any appropriate intermediate connections. For example, there may be provided a forked member 267 which is adapted to maintain its engagement with the said lever irrespective of the oscillatory movements thereof. The forked member 267 is mounted on a rod to which are imparted varying step-by-step movements heightwise from any suitable control means. A rod 269 engaging in a recess 270 in the forked member maintains the same in engagement with the selecting lever 95. For controlling the oscillating movements of the said selecting lever there is provided, as hereinbefore described, the rocking lever 306 which is furnished with the roller 307 engaged with the cylinder or barrel cam 308 rotatable upon the shaft 299 at half the speed of the continuously rotatable cam shaft 218 and connected with the selecting lever 95 through the intermediate connections previously described herein. The purpose of this control is to feed yarn to the needles first in one direction, for the duration of a complete knitting cycle of the co-operating knitting instrumentalities, and then in the opposite direction, during the next knitting cycle, and so on. For controlling the permanent splicing yarn carrier operating members 345 and 346 (Figure 34), the selecting lever 95 is linked up by means of the lower projecting end 101a of the vertical operating rod 101 whereby movement is imparted to the ground and side splicing yarn carriers. As will be appreciated this control is rendered inoperative during narrowing and widening transfer operations.

Control of transfer head for narrowing and widening

For racking the reversely cut ratchet wheels 165 and 166 included in this control, there are provided, as previously described, oppositely disposed pawls 167 and 168 mounted on individually movable slides 171 and 172. These slides are horizontally slidable and, as will be understood from the foregoing description, movable bodily up and down conjointly with the transfer head. Now, appropriate endwise movements of the said pawl-carrying slides 171 and 172 are obtained from two horizontally disposed rack slides 271 and 272, having their operative ends suitably extended to maintain engagement with the pawl-carrying slides during bodily up and down movement of the latter. The two rack slides 271 and 272 are actuated at respectively different times, one for narrowing and the other for widening and also for re-setting of the transfer points P after completion of the narrowing and widening operations. For actuating the rack slides there is provided a pair of levers 273 and 274 (Figure 1A), furnished with adjustable contact screws 275 and 276, and also with rollers such as 277 for co-operation with a cam unit (not shown) comprising axially spaced cam profiles, one for each lever, and, between the two, a neutral dwell track. By suitable axial movement of the cam unit on the continuously rotatable cam shaft 218,

derived from a control chain, either one or the other of the two rollers 277 can be engaged by the relevant cam profile, or both of the rollers may be located in the neutral dwell track. Therefore, by reason of this construction, it is impossible for both rollers to be engaged by the cam profile at any one time.

The successive stages in the conjoint operation of needles and associated instrumentalities in forming a welt will now be described with reference to Figures 13-24. In Figure 13, the instrument 110 is positioned to receive a loop L of the initial course drawn by the needle 3 over the nib 21a of the sinker 21. The said sinker 21 then commences to withdraw as a consequence of which the loop L is drawn into the loop-holding end of the instrument 110, as shown in Figure 14, the needle at this stage being in its lowest position. At the subsequent stage depicted in Figure 15, the sinker 21 has moved to its forward knocking-over position, the loop L still being retained by the instrument 110 and the needle 3 being partially raised. In Figure 16, the needle is shown raised still further so that the loop L is clear of the needle beard. As the needle 3 is finally raised to its full height and the sinker 21 is appropriately positioned to receive the fed yarn Y, as shown in Figure 17, the instrument 110 is slightly withdrawn—still retaining the loop L. Knitting now continues normally as illustrated in Figure 18. At the stage shown in Figure 19, a welt bar 278 is brought into action to draw off the welt fabric F extending between the needle 3 and the instrument 110 in the manner illustrated in Figure 20. To return the welt fabric F from the instrument 110 to the needle 3, the said instrument is first raised and then advanced to such an extent that the loop L is positioned, as shown in Figure 21, for penetration by the needle 3. At the stage illustrated in Figure 22, the needle 3 has been again fully raised this time to penetrate and receive the loop L. The instrument is partially retracted at this stage and then moved downwards as shown in Figure 23 thereby pressing the fabric F down onto the lower shelf 21b of the sinker 21. Figure 24 shows the instrument 110 fully retracted preparatory to the resumption of normal knitting.

Referring to Figure 25, it will be seen that each of the welt instruments 110 comprises a pair of complementary elements arranged side by side, these instruments being disposed between the sinkers 21 with the loop-holding end of each instrument located between a sinker and a needle. The picot instruments 111 are shown retracted.

In making a picot edge, each instrument 111 is moved to such a position that its operative end will take a loop such as L¹ from the adjoining nib 21a of a sinker 21d (Figure 26), this loop being retained by the instrument for a knitted course and then returned to the needle 3 as shown in Figure 27. Figure 28 shows the instrument 111 retracted, the fabric F being safely held by the welt instrument 110 by reason of the fact that the operative end of the instrument is at a higher elevation than that of the said welt instrument.

The machine constituting this invention is primarily intended for the manufacture, in a continuous series of automatic operations, of a complete fully fashioned hose blank such as that shown in Figure 30, comprising a welt 279 having a picot edge 280, anti-run courses 281 produced by transference of loops, a narrowed thigh 75

portion 282, a narrowed leg 283, spliced angle foot and heel portions 284 and 285, the splicing in which varies coursewise in prearranged courses, and spliced and narrowed toe portions 286.

In making this blank the loop spreading welt instruments 110 are first moved between the needles 3 to receive the yarn to be knitted into the first course. These instruments are then retracted so that the loops held thereby are retained. Knitting of the welt continues for a few courses when the fabric drawing off mechanism is engaged with the fabric. After further knitting, the picot course 280 is made by introducing the picot instruments 111 which take the sinker loops and transfer them to the adjoining needles, thereby forming a course of pelerine stitches. This is in contra-distinction to conventional practice, according to which knitted loops are transferred in the production of a picot course. Knitting is continued to complete the welt, whereupon the loops held by the loop spreading welt instruments 110 are transferred to the appropriate needles. After further knitting, the picot instruments 111 are again brought into commission to effect transference of sinker loops in the production of one or more anti-run courses 281. The two groups of transfer points P in the head are then brought into action at desired intervals adjacent to the selvedges of the blank throughout the knitting of the thigh, leg and angle, and at the same time the appropriate outside yarn carrier stops 192 and 193 are positioned to limit the coursewise extents of the movements of the corresponding yarn carriers 83. At desired locations adjoining the selvedges, during knitting of the ankle, the left-hand and right-hand splicing feeders are introduced in conjunction with introduction of the inside yarn carrier stops 194 and 195. The latter are moved inwardly and outwardly to varying extents to produce spliced areas of the desired shape. At the next stage both inside splicing stops and the appropriate outside yarn carrier stops are moved to the required positions, conjointly with operation of the transfer head, for widening at desired courses to produce the widened heel portions 287. If so desired the said widened heel portions may be made without employing the transfer head, in which case, the relationship between splicing and ground feeders may be suitably varied suchwise as to form cleared selvedges. For completing the spliced heel portions, variations of the appropriate inside and outside stops and introduction of the transfer head for narrowing is effected. Knitting of the foot is now continued with spliced portions adjacent to the selvedges of the blank. If desired, the positions of the inside splicing stops may be varied at suitable locations within the foot to produce shaped spliced areas. Knitting is proceeded with in this way until the toe narrowings are reached when suitable adjustments of the outside stops are made conjointly with actuation of the transfer head.

Knitting of the toe is continued, and then appropriate adjustment of the outside stops is effected, to complete the toe, after which a number of waste courses are knitted, and the blank is then pressed off.

A feature of the invention therefore includes a complete fully fashioned hose blank having an inturned welt including a picot course produced by the transference of sinker loops, the said

course being so disposed as to provide a picot edge at the fold of the welt.

The welt is followed by one or more anti-run courses also produced by the transference of sinker loops.

What we claim then is:

1. A full fashioned knitting machine with a single head including, in combination, a curved needle bed, an arcuate series of spring beard needles fixed within the said bed, means for imparting vertical movements to the needle bed, an arcuate series of individually movable sinkers, means for actuating the sinkers and causing them to co-operate with the said needles for loop forming and dividing purposes, and an arcuate series of individual beard pressers, one to each needle.

2. A full fashioned knitting machine with a single head including, in combination, a circular needle bed, a series of spring beard needles fixed within an arcuate portion only of the said bed, means for imparting vertical movements to the needle bed, an arcuate series of individually movable sinkers, means for actuating the sinkers and causing them to co-operate with the said needles for loop forming and dividing purposes, and an arcuate series of individual beard pressers, one to each needle.

3. A full fashioned knitting machine with a single head including, in combination, a curved needle bed, an arcuate series of spring beard needles fixed within the said bed, means for imparting vertical movements to the needle bed, an arcuate series of individually movable sinkers, means for actuating spaced sinkers seriatim to sink yarn between spaced needles, further means for effecting simultaneous actuation of all of the said sinkers for dividing, i. e. ensuring that the yarn is drawn around all of the needles knitting at any one time, and an arcuate series of individual beard pressers, one to each needle.

4. A full fashioned knitting machine with a single head including, in combination, a curved needle bed, an arcuate series of spring beard needles fixed within the said bed, means for imparting vertical movements to the needle bed, an arcuate series of individual sinkers, means for actuating spaced ones of the sinkers seriatim to sink yarn between spaced needles, individually movable members for effecting simultaneous actuation of all of the sinkers for dividing, vertically operable means for action on the said sinker-actuating members, said members being adapted to receive operative movements from the said vertically operable means and to transmit such movements horizontally to the sinkers, and an arcuate series of individual beard pressers, one to each needle.

5. A full fashioned knitting machine with a single head including, in combination, a curved needle bed, an arcuate series of spring beard needles fixed within the said bed, means for imparting vertical movements to the needle bed, an arcuate series of individual sinkers, means for actuating spaced ones of the sinkers seriatim to sink yarn between spaced needles, individually movable members for effecting simultaneous actuation of all of the sinkers for dividing, two arcuate members one arranged for action downwardly on appropriate ends of the said individually movable sinker-actuating members for depressing these ends and the other for action upwardly on the said ends for raising the same, the said sinker-actuating members being thereby adapted to receive operative movements from

the two arcuate members and to transmit such movements horizontally to the sinkers for the purpose specified, and an arcuate series of individual beard pressers, one to each needle.

5. A full fashioned knitting machine with a single head including, in combination, a curved needle bed, an arcuate series of spring beard needles fixed within the said bed, means for imparting vertical movements to the needle bed, an arcuate series of individual sinkers, means for actuating spaced ones of the sinkers seriatim to sink yarn between spaced needles, individually movable bell crank levers for effecting simultaneous actuation of all the sinkers for dividing the said levers having substantially vertically and horizontally disposed arms and the vertical arms being engaged with the sinkers, two arcuate members one arranged for action downwardly on the ends of the horizontal arms of the bell crank levers for depressing these ends and the other for action upwardly on the said ends for raising the same, the bell crank levers being thereby adapted to receive operative movements from the two arcuate members and to transmit such movements horizontally to the sinkers for the purpose specified and one arcuate series of individual beard pressers, one to each needle.

7. A full fashioned knitting machine according to claim 4, wherein each of the individually movable sinker-actuating members has attached to opposite sides thereof plates arranged to embrace the opposite sides of the corresponding sinker suchwise as to maintain engagement of the member with the sinker laterally.

8. A full fashioned knitting machine with a single head including, in combination, a curved needle bed, an arcuate series of spring beard needles fixed within the said bed, means for imparting vertical movements to the needle bed, an arcuate series of individual sinkers, individually movable members for actuating spaced ones of the said sinkers, seriatim to sink yarn between spaced needles, oscillatory cam means which are arranged concentrically with respect to the axis of the machine for and adapted to effect operation of the said members one after another, additional means for effecting simultaneous actuation of all of the sinkers for dividing, and an arcuate series of individual beard pressers, one to each needle.

9. A full fashioned knitting machine with a single head including, in combination, a curved needle bed, an arcuate series of spring beard needles fixed within the said bed, means for imparting vertical movements to the needle bed, an arcuate series of individually movable sinkers, means for actuating spaced sinkers seriatim to sink yarn between spaced needles, further means for effecting simultaneous actuation of all of the said sinkers for dividing, i. e. ensuring that the yarn is drawn around all of the needles knitting at any one time, a series of individual beard pressers, one to each needle, arranged in an arcuate series of groups, one only of the pressers of each group being formed with an operating butt and being adapted to transmit its movements to the companion non-butted pressers of the group, and cam means for action upon the said operating butts.

10. A full fashioned knitting machine according to claim 9, which includes, for operating the butted pressers, an oscillatory cam unit arranged concentrically with respect to the axis of the machine.

11. A full fashioned knitting machine with a single head including, in combination, a curved needle bed, an arcuate series of spring beard needles fixed within the said bed, means for imparting vertical movements to the needle bed, an arcuate series of individually movable sinkers, means for actuating spaced sinkers seriatim to sink yarn between spaced needles, further means for effecting simultaneous actuation of all of the said sinkers for dividing, i. e. ensuring that the yarn is drawn around all of the needles knitting at any one time, an arcuate series of individual beard pressers, one to each needle, and superimposed radially grooved arcuate carriers for accommodation of the sinkers, the upper of which carriers is also adapted to house the pressers.

12. A full fashioned knitting machine with a single head including, in combination, a curved needle bed, an arcuate series of spring beard needles fixed within the said bed means for imparting vertical movements to the needle bed, an arcuate series of individually movable sinkers, means for actuating spaced sinkers seriatim to sink yarn between spaced needles, further means for effecting simultaneous actuation of all of the said sinkers for dividing, i. e. ensuring that the yarn is drawn around all of the needles knitting at any one time, an arcuate series of individual beard pressers, one to each needle, and superimposed radially grooved arcuate carriers for accommodation of the sinkers, the upper of the said carriers being formed with grooves of a width to receive the pressers and the latter being recessed to receive the upper edges of the sinkers.

13. A full fashioned knitting machine with a single head including, in combination, a curved needle bed, an arcuate series of spring beard needles fixed within the said bed, means for imparting vertical movements to the needle bed, an arcuate series of individually movable sinkers, means for actuating spaced sinkers seriatim to sink yarn between spaced needles, further means for effecting simultaneous actuation of all of the said sinkers for dividing, i. e. ensuring that the yarn is drawn around all of the needles knitting at any one time, an arcuate series of individual beard pressers, one to each needle, and superimposed radially grooved arcuate carriers for accommodation of the sinkers, the upper of the said carriers being formed with grooves of a width to receive the pressers and the latter being stepped to receive the upper edges of the sinkers so that the stepped portion of each presser forms one wall of the companion sinker trick the other wall of which latter is constituted by the appropriate side of the radial groove in which the presser is located.

14. A full fashioned knitting machine with a single head including, in combination, a curved needle bed which is stationary so far as angular movement is concerned, an arcuate series of spring beard needles fixed within the said bed, means for imparting vertical movements to the needle bed, an arcuate series of individually movable sinkers, means for actuating the sinkers and causing them to co-operate with the said needles for loop forming and dividing purposes, an arcuate series of individual beard pressers, one to each needle, individually operable yarn carriers for presenting yarns to the needles and sinkers, the said carriers being movable angularly to variable extents about the axis of the machine, and controllable angularly movable stops for determining these extents.

15. A full fashioned knitting machine with a single head including, in combination, a curved needle bed which is stationary so far as angular movement is concerned, an arcuate series of spring beard needles fixed within the said bed, means for imparting vertical movements to the needle bed, an arcuate series of individually movable sinkers, means for actuating the sinkers and causing them to co-operate with the said needles for loop forming and dividing purposes, an arcuate series of individual beard pressers, one to each needle, individually operable yarn carriers for presenting yarns to the needles and sinkers, the said carriers being movable angularly to variable extents about the axis of the machine, controllable angularly movable stops for determining these extents, and mechanism comprising groups of laterally displaceable transfer points arranged at respectively opposite ends of the arcuate series of needles and adapted to receive knitted loops from appropriate needles and, after lateral displacement conjointly with vertical movement of the needle bed, to shed such loops for reception by receiving needles.

16. A full fashioned knitting machine with a single head including, in combination, a curved needle bed, an arcuate series of spring beard needles fixed within the said bed, means for imparting vertical movements to the needle bed, an arcuate series of individually movable sinkers, means for actuating the sinkers and causing them to co-operate with the said needles for loop forming and dividing purposes, an arcuate series of individual beard pressers, one to each needle, automatically operable mechanism for producing a welt, and ancillary mechanism for producing picot courses.

17. A full fashioned knitting machine with a single head including, in combination, a curved needle bed, an arcuate series of spring beard needles fixed within the said bed, means for imparting vertical movements to the needle bed, an arcuate series of individually movable sinkers, means for actuating spaced sinkers seriatim to sink yarn between spaced needles, further means for effecting simultaneous actuation of all of the said sinkers for dividing, i. e. ensuring that the yarn is drawn around all of the needles knitting at any one time, an arcuate series of individual beard pressers, one to each needle, and means for producing a welt including a picot course comprising an annular bed arranged concentrically with respect to the axis of the machine and a segmental portion of which is radially grooved and an arcuate series of loop spreading instruments located in the said grooved bed, spaced instruments being welt instruments and adapted for use in the formation of a welt and the intervening instruments being picot instruments and adapted for transference of sinker loops in the production of picot courses.

18. A full fashioned knitting machine with a single head including, in combination, a curved needle bed which is stationary so far as angular movement is concerned, an arcuate series of spring beard needles fixed within the said bed, means for imparting vertical movements to the needle bed, an arcuate series of individually movable sinkers, means for actuating the sinkers and causing them to co-operate with the said needles for loop forming and dividing purposes, an arcuate series of individual beard pressers, one to each needle, individually operable yarn carriers for presenting yarns to the needles and sinkers, the said carriers being movable angularly to variable extents about the axis of the machine, and controllable angularly movable stops for determining these extents.

said carriers being movable angularly to variable extents about the axis of the machine, and controllable angularly movable stops for determining these extents, the upper ends of the yarn carriers being disposed one above another and extending first outwardly and thence downwardly, the said downwardly extending portions being disposed at progressively greater distances radially from the axis of the machine and the yarn carrier disposed nearest to this axis having its upper end lowermost and the upper ends of the remaining yarn carriers, in order, being at progressively higher elevations.

19. A full fashioned knitting machine according to claim 18, wherein the upper ends of the yarn carriers have associated therewith superimposed pinions arranged in mesh with toothed members whereby the carriers are oscillated, the said pinions being carried by two axially opposed groups of tubular shafts, and the shafts of each group nesting compactly one within another.

20. A method of making a fully fashioned hose blank on a knitting machine according to claim 17, which includes the steps of causing the spaced welt instruments to take an initial course 25 of loops formed by co-operation of needles and sinkers, operating needles, sinkers and pressers

to produce welt fabric, the said initial course of loops being meanwhile retained by the said welt instruments, introducing the picot instruments and causing them to take sinker loops of the welt fabric and transfer the same to adjacent needles, so as to form a picot course, withdrawing the picot instruments, continuing to knit further welt fabric by co-operation of needles, sinkers and pressers as aforesaid, then operating the welt instruments to return the initial course of loops to the needles thus completing the welt, continuing the knitting, and forming anti-run courses by the re-introduction of the picot instruments and causing the latter to take sinker loops and transfer them to adjacent needles.

EDWARD SAMUEL BARSBY.
